UNITED STATES PATENT OFFICE

2,484,130

ARCH, ANKLE, AND LEG BANDAGE

Frank J. Thibault, Rochester, N. Y.

Application April 7, 1947, Serial No. 739,829

3 Claims. (Cl. 128—166.5)

1

The object of this invention is to provide a bandage that can be used as an arch and ankle support and a bandage for the lower leg.

Another object of the invention is to provide an elastic bandage that can be used as an arch and ankle support and a bandage for the lower leg.

Another object of the invention is to provide a bandage that will support the arch from a point above the calf of the leg.

Another object of the invention is to provide a bandage that comprises one long strap and two short straps attached transversely thereto, one of which short straps is adapted to go around the leg above the calf of the leg and the other short strap is adapted to go around the leg above the ankle, the long part of the strap being adapted to go around the ankle and the arch.

Another object of the invention is to provide a strap that will be fastened in place on the foot and the leg by snap fasteners, avoiding the use of adhesives.

These and other objects of the invention will be illustrated in the drawings, described in the specification and pointed out in the claims at the end thereof.

In the drawings:

Figure 1 is a plan view of the bandage spread out, that side of the bandage which is not applied to the skin being shown in the foreground.

Figure 2 is a front perspective view of the lower leg with the upper cross piece of the bandage as shown in Figure 1 fastened around the lower leg above the calf, and with the second cross piece shown idly on the bandage on the outside of the leg with the bandage passed down on the outside of the leg under the foot and up over the instep and around the ankle above the heel, with the long part of the bandage partially broken away but shown idly in position for the next step in the adjustment thereof.

Figure 3 shows the bandage in position on the leg as shown in Figure 2 with the extended part of the bandage crossed over the instep and around under the foot, the lower end of the bandage being broken away and shown idly extended in position for the next step in the adjustment thereof.

Figure 4 shows the bandage in position on the leg as shown in Figure 3 with the extended part of the bandage wrapped around the foot with an extra turn, with the lower end of the bandage being broken away and idly extended for the next step in the adjustment thereof.

2

Figure 5 shows the bandage in position on the leg as shown in Figure 4 with the extended part of the bandage carried up along the leg and attached to the extended flap shown at the right at the top of Figure 1, the leg in this figure being shown in side elevation, the second cross piece being shown idly on the bandage as appears in Figures 2, 3 and 4.

Figure 6 shows the bandage in complete position on the leg with the second cross piece closed around the leg above the ankle and held closed by the snaps.

Figure 7 shows the upper end of the bandage as shown in Figure 1 with the cross pieces folded over on the long piece of the bandage preparatory to rolling up the bandage.

Figure 8 shows the whole bandage rolled up into a small package for shipment.

Figures 9 and 10 show the male and female part of the standard snap fastener, a plurality of which are used on this bandage.

In the several figures of the drawings, like reference numerals indicate like parts.

In the drawings, reference numeral 1 indicates the long part of the bandage which is preferably made of elastic webbing, two inches more or less in width and fifty-four inches more or less in length. Reference numeral 2 indicates the upper cross piece of the bandage which likewise is made of elastic webbing two inches more or less in width and fifteen inches more or less in length. On the right hand end of the cross piece 2 is a tab 3 of elastic webbing extending downwardly therefrom.

Below the cross piece 2 is another cross piece 4 of elastic webbing two inches more or less in width and ten and a half inches more or less in length. Both of these cross pieces are fastened to the main web by rows of stitches arranged

40 in any suitable manner. The tab 3 is fastened to the cross piece 2 by rows of stitches in like manner. On the opposite ends of each of the cross pieces are placed the snap fasteners by which the ends of the cross pieces are fastened

45 together, the male parts of the snap fasteners being placed on one end of the cross piece and the female parts being placed on the other end of the cross pieces. It will also be noticed that on the right hand of these cross pieces four parts are shown and on the left hand end of the cross pieces, six parts are shown. This provides for adjustment in closing the snap fasteners together so that the cross pieces fit legs of various sizes.

On the tab 3, parts of six snap fasteners are 55 shown and at the bottom of the long strap 1 a

group of remaining parts of the fasteners are shown for the purpose of joining the lower end 5 of the long strap with the tab 3 shown at the top of Figure 1.

It will be seen that four of the fastener parts are shown at 5 in Figure 1 and six of the parts are shown at 3 in Figure 1. This also provides for adjustment, when the lower end of the strap is brought into contact with the tab 3 as will presently be described.

As shown in Figure 2, the long cross piece is placed around the leg above the calf and closed with the strap 1 preferably bearing directly against the leg, and the cross piece outside of the strap 1.

The web 1 extends down along the leg and the crosspiece 4 is left hanging idly on the web as shown in Figure 2. The web 1 passes down under the foot and over the instep and around the ankle above the heel, the web being shown idly extended and broken away.

From the position shown in Figure 2, the web 1 passes over the instep and down under the foot, the end of the web being shown idly extended and broken away. In this Figure 3, the web is shown crossing itself on top of the instep.

From the position shown in Figure 3, the web 1 is wrapped around the foot with an extra turn. This extra turn may be omitted but it is very desirable to use this extra turn for it binds the foot more snugly and keeps the bandage from slipping backward over the heel. This extra turn is shown in Figure 4. The long web 1 is then carried up on the inside of the leg and the parts of the snap fasteners on the tab 3 are connected with the parts of the snap fasteners indicated at 5 at the lower end of the web 1. In Figure 5, the cross piece 4 is shown idly extended. In Figure 6 this cross piece 4 is shown closed on itself, holding the web 1 close to the leg above the ankle. This completes the placing of the bandage on the leg.

It will be understood that while I have shown the web 1 starting down from the cross piece 2 on the outside of the leg, the cross piece 2 can be shifted around the leg so that the web 1 will start down on the inside of the leg with the snap fasteners on the outside of the leg, but I prefer to have the snap fasteners close themselves on the inside of the leg because they are less conspicuous.

It will also be understood that while I have shown the bandage applied to the right foot and leg, the same bandage can also be applied to the left foot and leg.

In Figure 7, I have shown a bandage with the two cross pieces folded over on each other and on the web 1 preparatory to rolling the bandage up into a small package for shipment, and Figure 8 shows the bandage after it has been rolled up into a small package for shipment.

In Figures 9 and 10 I have shown the two parts of the metal snap fasteners, the male part being shown in Figure 9 and the female part being shown in Figure 10.

It will also be understood that the long web 1 of the bandage will be made of different lengths to fit the legs of people of different heights and the cross pieces will be made of different lengths to fit legs of different sizes and will be spaced different lengths apart as may be needed to fit legs of different lengths.

It will also be understood that instead of snap fasteners any other suitable means for fastening may be used such as straps and buckles or hooks and eyes, etc.

It will also be understood that the cross strap 4 may be replaced by a loose strap or by a rubber band.

I claim:

1. In an arch, ankle and leg bandage the combination of a long web, a cross web fastened at the upper end of said long web and adapted to be fastened around the leg above the calf, the long web being adapted to extend down along the leg on one side thereof and under the foot and up over the instep and around the ankle above the heel and across over the instep and down under the foot and up along the other side of the leg, means for attaching the lower end of the long web to the said cross web, and a second cross web attached to the long web on the down side of said long web, namely below the junction between the above named cross web and the upper end of the long web and above the ankle, and being adapted to be closed around the long web on both sides of the leg at or above the ankle.

2. In an arch, ankle and leg bandage the combination of a long web, a cross web fastened at the upper end of said long web and adapted to be fastened around the leg above the calf, the long web being adapted to extend down along the leg on one side thereof and under the foot and up over the instep and around the angle above the heel and across over the instep and down under the foot and then around the foot and up along the other side of the leg, means for attaching the lower end of the long web to the said cross web, and a second cross web attached to the long web on the down side of said long web, namely below the junction between the above-named cross web and the upper end of the long web and above the ankle, and being adapted to be closed around the long web on both sides of the leg at or above the ankle.

3. In an arch, ankle and leg bandage the combination of a long web, a cross web fastened at the upper end of said long web and adapted to be fastened around the leg above the calf, the long web being adapted to extend down along the leg on one side thereof and under the foot and up over the instep and around the ankle above the heel and across over the instep and down under the foot and then around the foot and up along the other side of the leg, means for attaching the lower end of the long web when so extended upwardly to the said cross web on the said opposite side of the leg, and means attached to the long web and adapted to be placed around the leg at or near the ankle to hold the long web close to both sides of the leg.

FRANK J. THIBAULT.
